US0D1063565S

(12) **United States Design Patent** (10) **Patent No.:** **US D1,063,565 S**
(45) **Date of Patent:** **** Feb. 25, 2025**

(54) **CHOPSTICK**

(71) Applicant: **LANAN INTERNATIONAL CO., LTD.**, New Taipei (TW)

(72) Inventor: **Tsunenobu Tokura**, Kawanishi (JP)

(73) Assignee: **LANAN INTERNATIONAL CO., LTD.**, New Taipei (TW)

(**) Term: **15 Years**

(21) Appl. No.: **29/855,492**

(22) Filed: **Oct. 4, 2022**

(30) **Foreign Application Priority Data**

May 9, 2022 (JP) ..... 2022-009661 D

(51) **LOC (15) Cl.** **07-03**

(52) **U.S. Cl.** ..... **USPC D7/642**

(58) **Field of Classification Search**
